ATTORNEY

UNITED STATES PATENT OFFICE.

NATHAN D. COLE, OF NORWOOD, RHODE ISLAND.

EMBLEM-CHARM.

No. 838,499.

Specification of Letters Patent.

Patented Dec. 11, 1906.

Application filed January 27, 1906. Serial No. 298,289.

To all whom it may concern:

Be it known that I, NATHAN D. COLE, a citizen of the United States, residing at Norwood, county of Kent, State of Rhode Island, have invented a new and useful Improvement in Emblem-Charms, of which the following is a specification.

The nature of my invention consists in the improved construction of the joint between the upper and lower members of the emblem-charm, whereby one of the members will be firmly held between two shoulders, and thus prevented from movement relatively to the other member.

In the accompanying drawings, Figure 1 represents the front view of an emblem-charm provided with my improvement. Fig. 2 represents an edge view of the same. Fig. 2^a represents an edge view of the upper member of the charm without the lower member. Fig. 3 represents the front view of an emblem-charm of different construction. Fig. 4 represents an edge view of the same. Fig. 5 represents a longitudinal section of the joint between the upper and lower members. Fig. 6 represents an edge view of the same.

In the drawings, Figs. 1 and 2, A represents the head or upper member of the charm, and B the lower member, the said members being jointed to each other by means of the hollow wires *a a*, soldered to the base of the upper member, and the intermediate hollow wire *b*, soldered to the upper edge of the lower member, the said upper and lower members being then connected together by means of the pin *c*, which passes longitudinally through the bores of the said hollow wires *a a* and *b*. Heretofore in the manufacture of such charms the wire *c* has been driven in tightly and the ends of the said wire upset, so as to

hold the upper and lower members in the same plane with each other; but it is found in practice that the joint so formed is liable to become loose, so as to require repair, and in order to obviate this difficulty I have provided 45 the hollow wires *a a* with the attached collars *d d*, which serve to form the shoulders *e e*, between which the upper edge *f* of the lower member is held, and by means of the said shoulders the upper and lower members are 50 prevented from turning upon the joint-pin *c*, which fastens the said members together.

Another form of construction is shown in Figs. 3 and 4, in which the cape *g* is employed to cover the hollow wires *a a* and *b*, which 55 serve to form the joint between the upper and lower members, the hollow wires *a a* being soldered to the scroll-piece *h* of the lower member B and the hollow wire *b* soldered to the head or upper member A, the said hollow 60 wire *b* and the connected cape *g* being provided with the shoulders *e e*, as shown in Fig. 6, the said shoulders serving to embrace the sides of the said scroll-piece *h*, and thus serve to prevent the movement of the upper and 65 lower members relatively to each other. The said members A and B may be readily connected or disconnected by means of the fastening-pin *c*, so that changes in either of the said members may be readily effected. 70

I claim as my invention—

In an emblem-charm, the combination of the upper and lower members, with the longitudinally - pinned tubular joint and the abutting shoulders which serve to prevent 75 the swinging movement of the said members.

NATHAN D. COLE.
